UNITED STATES PATENT OFFICE.

HENRY N. WADE, OF MILWAUKEE, WISCONSIN, ASSIGNOR TO THE CUTLER-HAMMER MFG CO., OF MILWAUKEE, WISCONSIN, A CORPORATION OF WISCONSIN.

RHEOSTAT.

Application filed July 1, 1918. Serial No. 242,712.

To all whom it may concern:

Be it known that I, HENRY N. WADE, a citizen of the United States, residing at Milwaukee, in the county of Milwaukee and State of Wisconsin, have invented new and useful Improvements in Rheostats, of which the following is a full, clear, concise, and exact description, reference being had to the accompanying drawing, forming a part 10 of this specification.

This invention relates to rheostats and more particularly to those of the fluid type.

In practice such rheostats are frequently desired for alternating current systems 15 wherein it is important to provide for gradual resistance variations between wide limits and for preservation of phase balance. On the other hand, much difficulty has been experienced in producing a fluid 20 rheostat affording such control, efforts in this direction having led to complicated and costly structures, and the present invention has among its objects to provide a simple and efficient fluid rheostat to meet such 25 requirements.

A further object is to provide a fluid rheostat wherein the electrodes are fixedly mounted and the fluid is raised or lowered with respect thereto in a manner greatly to 30 simplify the control means required and to facilitate automatic regulation thereof.

A further object is to provide a fluid rheostat wherein the height of the fluid may be regulated by air pressure and wherein 35 the supply of air may be utilized to effect circulation of fluid between the electrodes.

Other objects and advantages will hereinafter appear.

In the accompanying drawing wherein is illustrated an embodiment of the invention,

Figure 1 is a side elevational view, partly in section, of the rheostat, the control means therefore being schematically and diagrammatically illustrated; while,

Fig. 2 is a similar end view of the rheostat.

Referring to the drawing, the same shows a rheostat arranged to control a three phase 50 alternating current circuit a , b , c , and comprising three sets of electrodes d , e , f , extending downwardly to different levels

within an electrolyte tank 6 and fixed with relation thereto.

The electrodes of each set are similar to each other while the several sets of electrodes differ from one another only in length and in the shape of their lower portions, the electrodes d being longest and being furthermore gradually tapered and the extreme lower ends thereof being extended to provide reduced surfaces d' for uninterrupted contact with the electrolyte. The electrodes f are relatively short, their lower ends being more bluntly tapered, whereas, 65 the electrodes e are similar to the electrodes f but of a length intermediate of the electrodes d and f .

The aforesaid sets of electrodes are symmetrically arranged according to length, 70 and equally spaced from one another. That is to say, the electrodes d are arranged at equal intervals. The electrodes e are arranged midway between adjacent electrodes d while the electrodes f are similarly arranged midway between adjacent electrodes 75 d and e .

The several electrodes are connected to the respective conductors a , b , c , of the controlled circuit in a definite sequence which 80 is as follows: Beginning at the left of Fig. 1, the first electrode is connected to conductor c , the second to a , the third to b , the fourth to c and thence on in the same order. By this arrangement each of the phase 85 conductors a , b and c is connected to the same number of electrodes of each length, whereby the effective electrode area is equally apportioned among the phases under 90 all conditions of immersion, the first and last electrodes of the series being for this purpose regarded as one, since their outer surfaces are electrically inactive whereby their combined effective areas exactly equal the effective area of any single intermediate 95 electrode of the same length.

Moreover by the foregoing arrangement of the electrodes a like number of current paths of equal length is at all times provided between all phases of the controlled 100 circuit, whereas upon predetermined rises in level of the electrolyte the length of each path is reduced by half and the number of paths is increased two-fold while the effec-

tive electrode area is also increased. Obviously a drop in the electrolyte level produces similar effects but in an opposite sense while the taper of the lower ends of the electrodes *e* and *f* insures a smooth resistance variation during the aforesaid transformations.

For mounting the electrodes fixedly in the relation described, said electrodes are preferably provided adjacent their upper ends with three triangularly arranged openings 7 through which extend a like number of parallel rods 8, said rods being arranged above and longitudinally of the tank and being terminally supported by a pair of blocks 9 of wood or other suitable material which are fixed across the tank adjacent its ends. The electrodes are provided with annular insulating supports 10 which are interposed between adjacent electrodes and are of suitable thickness to provide the necessary spacing therebetween. Each of said supports is provided with a pair of oppositely arranged annular flanges 11 which are of materially greater diameter than the rods and are adapted to fit snugly within the openings 7 in the electrodes whereby said electrodes are supported in spaced and insulated relation to the rods and to each other.

To provide for varying the height of the electrolyte pneumatically, the tank 6 which is preferably rectangular in cross section, is provided with a displacement chamber 12 located below the main electrolyte chamber 13 and formed by a pair of abutting interior walls 14 and 15. The former wall extends horizontally and is located an appreciable distance below the electrodes while the latter wall extends from the inner end of the wall 14 downwardly adjacent the side of the tank and terminates a short distance above the bottom thereof, thus providing an elongated port 16 and a passage 16^a between said chambers.

Compressed air from a continuously acting pump 17 or other suitable source is supplied to the displacement chamber through a conduit 18, the supply of air to said chamber being regulable by means of a throttling valve 19 and being controllable selectively through a manually actuatable valve 20 and an electro-responsive valve 21, said last mentioned valve being biased to closed position by gravity or otherwise and having an actuating winding 22 to be energized from a suitable current source *I*, *I'* through a manually operable switch 23.

The throttle valve 19 is located in the conduit 18 preferably adjacent the pump 17 and is adapted to be set in a fixed position for regulating the rate of air admission to the displacement chamber 12. The manually operable valve 20 is located in a branch or by-pass conduit 24 connecting the conduit 18 with the intake of the pump. The electro-

responsive valve 21 is located in a valve chamber 25 which is in open communication with the conduit 18 while the discharge port of said valve is connected by a pipe 26 with the by-pass conduit 24, said latter conduit being furthermore provided with a pipe 27 connecting the same with the interior of the electrolyte tank above the highest level of electrolyte therein. The top of said tank is furthermore enclosed by means of a cover 28.

Each of the valves 20 and 21 is of sufficient capacity when fully open to permit passage of an appreciably greater volume of air than that supplied by the pump whereby upon opening of either of said valves air escapes from the displacement chamber for decreasing the immersion of the electrodes while the air supplied by the pump is by-passed through the conduit 24 without entering said chamber. Obviously by varying the degree of opening of the valve 20 or by intermittent opening and closing of the valve 21 the rate of increase or decrease in immersion of the electrodes may be finely adjusted. Furthermore by means of the construction described, the air escaping from the displacement chamber through the valves 20 and 21 is returned to the pump through the by-pass 24 and thereafter reconducted to said chamber, while any air escaping within the main electrolyte chamber 13 is collected beneath the cover 28 and similarly returned to the pumping system through the conduit 27 whereby the air is used repeatedly and the electrolyte vapor suspended therein is conserved.

For cooling the electrolyte the usual cooling coils 29 are arranged within the tank adjacent the electrodes and a further set of cooling coils 30 is arranged immediately below the electrodes for absorbing the heat generated while the electrolyte occupies only the lower levels and is therefore not effectively cooled by the coils 29.

For causing circulation of the electrolyte and facilitating cooling thereof by said coils, a plurality of reduced openings 31 are provided in the wall 14 preferably adjacent its junction with the wall 15 whereby compressed air escapes from the displacement chamber in the form of bubbles which rise to the surface thus inducing a flow of electrolyte between the electrodes and against the cooling coils. Also, following expulsion of the electrolyte from the displacement chamber, the air thereafter supplied to said chamber by the pump escapes through the port 16 and the passage 16^a for further increasing the circulation of the electrolyte. The passage 16^a and the line of openings 31 being arranged at right angles to the planes of the electrodes as described, the induced flow of electrolytes will be chiefly between and parallel to the electrode surfaces whereby the most efficient circulation is obtained.

While the afore-described rheostat is

capable of general application, the same is particularly adapted to control the motor secondary resistance of a motor generator set such as that illustrated schematically in Fig. 1.

As there illustrated, the lines *a*, *b*, *c* controlled by the rheostat, are connected in the rotor circuit of a three phase induction motor 32 coupled to a generator 33 and provided 10 with an energy storing fly-wheel, said motor being supplied with primary current from lines L^1 , L^2 , L^3 . The rheostat is thus adapted to provide secondary current regulation both under starting and running conditions 15 of the motor. Furthermore during running it is desirable to reduce the motor speed automatically by increasing the resistance of its secondary circuit upon an increase in load thereby permitting the fly-wheel to assume 20 its proper share of such increment. For this purpose the energizing circuit of the valve actuating winding 22 is controlled by a normally open polyphase relay 34 having its energizing windings 35 connected 25 to a transformer 36 arranged in the primary supply circuit of the motor 32 whereby the valve 21 is opened automatically for reducing the air pressure within the displacement chamber and thereby increasing 30 the resistance of the rheostat upon increase in load upon the motor, as indicated by a rise in current by its primary circuit.

Obviously said relay may be calibrated to provide for response and release thereof with 35 consequent opening and closing of the valve 21 at any desired degree of current variation in the motor primary circuit, whereby the rheostat resistance is automatically regulated according to varying load conditions 40 of the motor while manual control of the motor by means of the rheostat is also provided.

What I claim as new and desire to secure by Letters Patent is:

45 1. In a fluid rheostat, the combination with an electrolyte tank, of a plurality of electrodes extending different distances therewithin, said electrodes being arranged and connected in circuit to provide for increase in the number and decrease in length of the current paths therebetween upon variation in the vertical relation of the electrolyte thereto.

50 2. In a fluid rheostat, the combination with an electrolyte tank, of a plurality of electrodes extending different distances therein and adapted to coact with the electrolyte to vary the resistance of a polyphase circuit, said electrodes being so arranged and so connected to said circuit as to provide a like number of current paths of equal length between the phases of said circuit under all conditions.

55 3. In a fluid rheostat, the combination with an electrolyte tank, of a plurality

of electrodes extending different distances therein and adapted to coact with the electrolyte to vary the resistance of a polyphase circuit, said electrodes being so arranged and so connected to said circuit as to provide a like number of current paths of equal length between the phases of said circuit under all conditions and to provide for increase in the number of said paths upon given variations in height of said electrolyte. 70

4. In a fluid rheostat, the combination with an electrolyte tank, of a plurality of electrodes extending different distances therein and adapted to coact with the electrolyte to vary the resistance of a polyphase circuit, said electrodes being so arranged and so connected to said circuit as to provide a like number of current paths of equal length between the phases of said circuit under all conditions and to provide for increase in the number and decrease in length of said paths upon given variations in height of said electrolyte. 75

5. In a fluid rheostat, the combination with an electrolyte tank, of a plurality of electrodes extending different distances therein and adapted to coact with the electrolyte to vary the resistance of a polyphase circuit, said electrodes being so arranged and so connected to said circuit as to provide a like number of current paths of equal length between the phases of said circuit under all conditions, and to provide for doubling the number and halving the length 100 of said paths upon a given variation in height of said electrolyte. 95

6. In a fluid rheostat, the combination with an electrolyte tank, of a plurality of electrodes extending different distances therein and adapted to coact with the electrolyte to vary the resistance of a polyphase circuit, said electrodes being so arranged and so connected to said circuit as to provide a like number of current paths of equal length between the phases of said circuit under all conditions, and to provide for doubling the number and halving the length 105 of said paths repeatedly upon given consecutive variations in level of said electrolyte. 110

7. In a fluid rheostat, the combination with an electrolyte tank, of a plurality of electrodes projecting different distances therewithin and adapted to coact with the electrolyte for controlling the resistance of a polyphase circuit, adjacent electrodes being connected to successive phase conductors of said circuit and said electrodes being symmetrically arranged according to their respective degrees of projection within said 120 tank. 115

8. In a fluid rheostat, the combination with an electrolyte tank, of a plurality of fixed electrodes extending unlike distances therewithin and adapted upon rise in level 130

- of the electrolyte to make contact therewith in distinct steps, the electrodes constituting the first step being equally spaced from one another, the electrodes of the second step being medially interposed between adjacent electrodes of the first step and the electrodes of the third step being similarly arranged between adjacent electrodes of the two former steps.
10. 9. In a fluid rheostat, the combination with an electrolyte tank, of a plurality of electrodes extending unlike distances therewith and adapted upon rise in level of the electrolyte to make contact therewith and to be immersed therein in distinct steps, the longest electrodes constituting the first step being equally spaced from one another, the electrodes next in length constituting the second step and being medially interposed between adjacent electrodes of the first step and the shortest electrodes constituting the third step and being similarly arranged between adjacent electrodes of the former two steps.
15. 10. In a fluid rheostat, the combination with an electrolyte tank, of a plurality of electrodes extending unlike distances therewith and adapted upon rise in level of the electrolyte to make contact therewith and to be immersed therein in distinct steps for varying the resistance of a polyphase circuit, the electrodes constituting the first step being equally spaced from one another within the tank, the electrodes of the second step being medially interposed between adjacent electrodes of the first step and the electrodes of the third step being similarly arranged between adjacent electrodes of the former two steps and adjacent electrodes being connected to successive phase conductors of said circuit whereby the total resistance is equally apportioned among the phases of the controlled circuit under all conditions of immersion of said electrodes.
20. 11. In a fluid rheostat, the combination with an electrolyte tank, of a plurality of electrodes projecting therewithin and adapted to vary the resistance of the rheostat upon variation in height of the electrolyte, said tank having a displacement chamber located below said electrodes and in communication with the space thereabout and means for introducing gas under pressure to said displacement chamber for varying the height of electrolyte about said electrodes.
25. 12. In a fluid rheostat, the combination with an electrolyte tank, of a plurality of electrodes extending therewithin for coaction with the electrolyte, said tank having a chamber located below said electrodes, and means for supplying compressed air to said chamber continuously, said chamber having restricted openings providing for escape of air therefrom for causing circulation of electrolyte about said electrodes.
30. 13. In a fluid rheostat, the combination with an electrolyte tank, of a plurality of electrodes extending therewithin for coaction with the electrolyte, said tank having a chamber located below said electrodes, and means for supplying compressed air to said chamber, the latter having a plurality of reduced openings located laterally of said electrodes and providing for a continuous escape of air therethrough for causing circulation of the electrolyte between and across said electrodes.
35. 14. In a fluid rheostat, the combination with an electrolyte tank, of a plurality of electrodes extending therewithin for coaction with the electrolyte, said tank having a displacement chamber located below said electrodes and having a port communicating with the interior of said tank, means for supplying compressed air to said chamber to expel electrolyte therefrom for varying the immersion of said electrodes, said chamber having a plurality of reduced openings providing a continuous escape of air upwardly within said tank for inducing circulation of the electrolyte about said electrodes.
40. 15. In a fluid rheostat, the combination with an electrolyte tank, of a plurality of electrodes extending therewithin for coaction with the electrolyte, said tank having a displacement chamber located below said electrodes and having a port located near its bottom and laterally of the several electrodes for providing communication with the interior of said tank, and means for supplying compressed air to said chamber and exhausting air therefrom for varying the distribution of the electrolyte within said chamber and said tank to vary the immersion of said electrodes, said port being adapted under given conditions to provide for escape of air upwardly within said tank for inducing circulation of the electrolyte between and across said electrodes.
45. 16. In a fluid rheostat, the combination with an electrolyte tank provided with an interiorly located displacement chamber in open communication therewith, of a plurality of electrodes extending downwardly within said tank above said chamber for coaction with the electrolyte, a continuously acting pump for supplying compressed air to said chamber to expel electrolyte therefrom for varying the immersion of said electrodes, and means for collecting any air escaping from said tank together with the electrolyte vapor suspended therein and conducting the same to the intake of said pump to be returned to said chamber thereby.
50. 17. In a fluid rheostat, the combination with an electrolyte tank, of a plurality of electrodes adapted to co-operate with the electrolyte therein, said tank having a chamber located below said electrodes, and means

for effecting passage of fluid from said chamber through said electrolyte.

18. In a fluid rheostat, the combination with an electrolyte tank, of a plurality of electrodes adapted to co-operate with the electrolyte therein, said tank having a chamber located below said electrodes, and means for supplying compressed air to said chamber, the latter having a plurality of reduced 10 openings providing for escape of air therethrough.

19. In a fluid rheostat, the combination with an electrolyte tank, of a plurality of electrodes adapted to co-operate with the 15 electrolyte therein, said tank having a chamber located below said electrodes, and means for supplying compressed air to said chamber, the latter having a plurality of reduced openings for permitting escape of air

through the electrolyte adjacent said electrodes. 20

20. In a liquid rheostat, the combination with a plurality of electrodes, of means comprising a perforated member for effecting the passage of gas bubbles through the 25 liquid.

21. In a liquid rheostat, the combination with a plurality of electrodes, of a perforated hollow member located below the electrodes, and means for forcing a gas 30 through the perforations.

22. In a liquid rheostat, the combination with a plurality of electrodes, of means for causing air bubbles to sweep upwardly past said electrodes. 35

In witness whereof, I have hereunto subscribed my name.

HENRY N. WADE.
